Primary Examiner — Brett Miller*Assistant Examiner* — Rani J Abdallah(74) *Attorney, Agent, or Firm* — Sheppard, Mullin, Richter & Hampton LLP(57) **CLAIM**

I claim the ornamental design for the bottle, as shown and described.

DESCRIPTION

FIG. 1 is a perspective view of an ornamental design for a bottle;

FIG. 2 is a first side elevational view thereof;

FIG. 3 is a second side elevational view thereof;

FIG. 4 is a third side elevational view thereof; and

FIG. 5 is a fourth side elevational view thereof.

FIG. 6 is a top plan view thereof; and,

FIG. 7 is a bottom plan view thereof.

The broken lines in the drawings depict portions of the bottle that form no part of the claimed design.

1 Claim, 7 Drawing Sheets(56)
